DESIGN FOR A SUCTION CLEANER DUST-BAG

Clarence G. Frantz, Cleveland Heights, Ohio, assignor to The Apex Electrical Manufacturing Company, Cleveland, Ohio, a corporation of Ohio

Application May 1, 1934, Serial No. 51,607

Term of patent 14 years

To all whom it may concern:

Be it known that I, Clarence G. Frantz, a citizen of the United States of America, and a resident of Cleveland Heights, in the county of Cuyahoga and State of Ohio, have invented a new, original, and ornamental Design for a Suction Cleaner Dust-Bag, of which the following is a specification, reference being had to the accompanying drawing, forming part thereof.

Figure 1 is a plan view, Figure 2 is a side elevational view, and Figure 3 is a perspective view of a suction cleaner dust bag showing my design.

I claim:

The ornamental design for a suction cleaner dust-bag, as shown.

In witness whereof, I have hereunto set my hand this 17th day of April, 1934.

CLARENCE G. FRANTZ.
